UNITED STATES PATENT OFFICE.

JONATHAN W. C. GILMAN, OF BOSTON, MASSACHUSETTS.

WRITING-BOOK.

No. 902,959.

Specification of Letters Patent.

Patented Nov. 3, 1908.

Application filed April 11, 1908. Serial No. 426,449.

To all whom it may concern:

Be it known that I, JONATHAN W. C. GILMAN, of Boston, in the county of Suffolk and State of Massachusetts, a citizen of the 5 United States, have invented a new and useful Improvement in Writing-Books, of which the following is a specification.

Books for the teaching and practice of hand-writing are either made in book form, 10 that is bound, or the writing to be copied is printed on cards with which practice paper is inclosed in an envelop, the whole going by the name of "renewable copy-book". This latter form of "book", as it is called, has 15 many advantages which are recognized, but still in some localities a book in which all the features are bound together, as in the old-fashioned copy-book, is preferred.

My invention therefore relates to a bound 20 copy-book and is an improvement upon the old form of book. In the old form the book was bound upon the short side generally and the copy printed at the top of each page, thus taking up one or more lines which otherwise 25 might be used for writing. In such a book the paper has to be of a character both to receive the printer's ink with which the copy is printed and also the writing ink which the pupil uses. Such a paper is expensive and its use adds to the cost of the 30 book. The shape of the book is such that when open with the page to be written on in front of the pupil, that is in the middle of the desk, the opposite page and the leaves and 35 cover beneath it will hang more or less over the edge of the desk unless the desk is fairly wide. If the book is doubled back on itself the under page gets soiled from rubbing against the top of the desk. Moreover, in 40 writing upon the right-hand page of such a book the pupil's left hand and arm usually rest upon the left-hand page to hold the book steady and hence are liable to and usually do soil the left-hand page so that in 45 the ordinary school the book is not as neat and clean as it should be. Such books too as ordinarily made usually buckle more or less near the place where they are sewed so that, for example, in writing upon the left-hand 50 page the pupil either has to reach away across the page to hold its right-hand edge flat or else has an unsatisfactory surface upon which to write. Moreover, the ink-well is ordinarily at the right-hand upper 55 corner of the desk and if the pen is too full, ink is apt to drop upon the right-hand page

as the pen is carried across it to a point where the writer is to use it on the left-hand page. Another disadvantage of this type of book is that no provision is made in the book 63 itself whereby the pupil may have an opportunity of memorizing or visualizing the copy. It is to provide a book which shall be free from these faults and which shall have other advantages not found in the old copy- 65 book that my invention has been made.

It will be understood by reference to the drawings, in which—

Figure 1 is a plan of a book embodying my invention, the book and its cover being 70 opened out flat. Fig. 2 is a longitudinal section thereof. Fig. 3 is a longitudinal section of the book opened in one way. Fig. 4 is a plan view showing the book doubled back. Fig. 5 is a longitudinal section of the 75 book shown in Fig. 4. Fig. 6 is a longitudinal section of the book closed and ready to be put away. Fig. 7 is a longitudinal section of the book when closed by the pupil at the end of a writing lesson. 80

The book comprises a cover, a series of comparatively wide blank writing leaves and narrow or copy leaves. The cover comprises three sections A, A¹, A². The leaves B, B¹, etc. and the narrow or copy leaves C, C¹, 85 which are relatively narrow leaves carrying the copy, alternate throughout the book, a double narrow copy leaf C², C³ also lying between the two middle leaves of the book and another double narrow copy leaf C⁴, C⁵ lying 90 between the two outside leaves of the book and the cover. The whole is stitched to the cover along the line a which divides section A of the cover from section A¹, A² being a section of the cover intended to 95 wrap over the section A when the book is closed as well as for the other purposes below described. The leaves are preferably perforated as at b or otherwise weakened along their line of fold so that when the book 100 is open, its hinge being weak, it will straighten out and the whole lie practically flat. Each narrow copy leaf comprises two sections C, C¹, and each side of each section carries one or more lines of copy printed upon it, c indicating the copy on one side of the copy flap and c¹ indicating the copy on the reverse side (see Fig. 5). 105

The book as shown is intended to be used in the following manner: The top of a page 110 instead of being along one of the outer edges, as in the usual bound copy-book, is in the

middle of the book, and it will be seen from Fig. 1 that the narrow copy leaf is located just above or beyond what may be termed the top of a page so that the pupil has the 5 entire page upon which to practice. It will also be seen that the narrow leaf may lie flat as shown in Figs. 1 and 2 or can be adjusted as to its angle with the eye as shown in Figs. 3, 4, and 5, being held by the pupil in such a 10 position as will bring the plane of the narrow leaf at the proper angle to the line of vision and this adjustment may be changed as occasion may require as the pupil writes down the page. In using the book in the preferred way the pupil writes first on page 1 15 using the copy c^1 on the first narrow leaf C . He then turns over to page 2 and follows the copy on the side c of the second narrow leaf C^1 , then page 3, using the copy on the reverse 20 side c^1 of narrow leaf C^1 , and so on through the book. The perforations b weaken the paper along its line of fold so that the book not only lies flat but when folded takes the 25 fold smoothly and without any tendency to buckle.

I prefer to provide upon the side c^1 of narrow copy leaf C^2 and the side c of narrow copy leaf C^3 , which form the middle section of the book, practice exercises which are not intended to be copied into the book, but which may be used with loose sheets, such exercises giving the pupil facility in acquiring the mechanical movements of the arm and wrist which are necessary for good hand-writing and yet not of a character which need be preserved as tests of penmanship, and the same is true of the copies upon the sides c and c^1 of the narrow leaves C^4 and C^5 , respectively, which are bound between the 30 cover and the wide leaves. Instead of this use the copy upon the sides of the narrow leaves, above referred to, may be of sentences to be memorized.

As intimated above, the cover may be used either as shown in Fig. 1, *i. e.*, lying out flat, or in the form shown in Fig. 3 where the section A^1 is folded to protect the page not in use and in the latter case the book may be doubled back as shown in Figs. 4 and 5 45 where the cover serves to protect the page from rubbing on the desk (see Figs. 4 and 5). Thus in Fig. 1 the section A^2 of the cover performs no useful function. In Fig. 3, however, it is shown turned over to form 50 a cover or protection from blotting or from dirt to the part of the book which is not in use, and in Figs. 4 and 5 this idea is still further developed by turning the part of the book which is not in use back upon itself 55 so that the book is reduced in area practically to the size of one page and the size of a narrow leaf attached to it. In Fig. 6 it holds the book closed so that in falling to the floor it remains closed. Thus the section 60 A^2 performs in fact a new and useful func-

tion which is not performed by any part in the usual form of copy book.

In using the book, the pupil may either open the book to the position shown in Fig. 2, Fig. 3, or Fig. 5. In either case he adjusts the copy leaf to the proper angle, changing its position as he writes down the page. To write the copy from memory he turns down the copy leaf, thus entirely concealing the copy from view, and if further practice is desirable he can turn the copy into sight again.

The utility of my invention will be understood from what has been said above. Its features may be utilized in other forms of copy books, but the above describes the best embodiment now known to me. One advantage of this form of book is that of economy of construction, in that the engraved copies may be printed upon paper best suited 80 therefor and made into copy leaves, while ordinary writing paper will answer for the greater part of the book. The small size of the copy leaves allows a large number of copies to be combined in the same form and 85 printed at the one impression, copies for two books, for example, being thus printed at the expense attending the printing of the copy lines for one-half of a book of the old style. Moreover, the construction of the 90 book as described combines with the regular features of the book the reverse sides of the double copy leaves C^2 , C^3 , C^4 , C^5 which may be used for practice exercises as above described.

I have shown in Fig. 3 a way in which the book may be closed quickly by the pupil without danger of blotting the opposite page, thus showing another use for the cover which is advantageous. In this case the pupil has been writing upon the left-hand page and the word having been given to close the books the cover is folded in as shown in Fig. 3. The book being then closed, if the ink where the pupil has been writing is not entirely dry, the ink may blot the fold or section A^2 of the cover but not the opposing page of the book which will thus be left 105 fresh and clean for the next lesson.

What I claim as my invention is:—

1. A copy book having a series of blank leaves for writing and a series of narrow leaves each narrow leaf being located between a pair of said blank leaves, each narrow leaf having a copy printed on both sides 110 of it.

2. A copy book having a series of blank leaves for writing and a series of narrow leaves each narrow leaf being located between a pair of said blank leaves, a double narrow leaf being located at the middle of the book, a cover and a double narrow leaf lying between said cover and a blank leaf each narrow leaf having a copy printed on 125 both sides of it.

3. In a copy book for writing exercises, blank leaves for writing and narrow leaves containing copy bound together, said narrow leaves alternating with said blank leaves. 40
- 5 4. A copy book having a series of blank leaves for writing and a series of narrow leaves containing copies bound together, said narrow leaves alternating with said writing leaves, all of said leaves being perforated 45
- 10 along the line upon which they are bound, as described.
- 5 5. A copy book for writing exercises comprising blank leaves for writing and narrow leaves containing copy, said blank leaves 50
- 15 and said copy leaves alternating throughout the book, said book being provided with a cover comprising three sections, two of said sections being bound outside the leaves to form a protection therefor and a third section extending beyond one of said protecting 55
- 20 sections and being of substantially the same area therewith.
6. A copy book having blank leaves for writing and narrow leaves containing copy alternately arranged with said blank leaves, and a cover comprising three sections, two of said sections being bound outside said leaves 60
- 25 and forming a protection therefor, the third section being of substantially the same area
- 30 as one of said other sections whereby it may be folded to protect an open page as described. 65
7. A copy book having blank leaves for writing and narrow leaves containing copy, said narrow leaves and said blank leaves being alternately arranged, said leaves being adapted to be doubled back upon themselves, and a cover comprising three sections, two 70
- 35

of said sections being bound with said leaves to form a protection therefor, the third section being of substantially the same area as each of the other sections and a continuation of one of said other sections whereby it may be folded over to protect and form a rest for an exposed doubled back leaf as described. 45

8. A copy book comprising blank leaves for writing and narrow leaves containing copy alternately arranged, and a cover comprising three sections, two of said sections 50

being bound with said leaves to form a protection for the two outside pages and one of said sections being adapted to fold over one of the open pages of the book whereby said page when the book is open will be protected 55

from blots or dirt and when the book is closed from contact with the opposite page to blot it.

9. In a copy book for writing exercises, blank leaves for writing bound along one 60

edge, and a series of narrow leaves alternating with said blank leaves and bound along the bound edges of said blank leaves, said narrow leaves containing copy on each side thereof. 65

10. In a copy book for writing exercises, blank leaves for writing, and a series of narrow leaves containing copy, said blank leaves and said copy leaves being bound, two of said narrow leaves being located at the mid- 70

dle of the book. 75
